UNITED STATES PATENT OFFICE.

AUGUSTA DU BUISSON HOPKINS, OF NEW ORLEANS, LOUISIANA.

GRATER.

Application filed December 5, 1927. Serial No. 237,736.

This invention relates to fruit and vegetable graters, and the principal object of the same is to provide a strictly sanitary grater in which the grating operation is performed 5 in a closed casing, so that foreign material can not obtain access thereto, and in which the operating parts are shielded so that there is no danger of injury being done to the operator incidental to the operating of the 10 machine.

Another object of the invention is the construction of a grater which is peculiarly reinforced, or braced to prevent sagging, or twisting out of shape, of the base structure 15 of the same, whereby a very durable and efficient machine is produced.

This application discloses certain new and useful improvements made to my machine as disclosed in my prior United States Patent 20 No. 977,872, patented Dec. 6, 1910.

With the foregoing and other objects in view, my invention comprises certain novel constructions, combinations and arrangements of parts as will be hereinafter fully 25 described, illustrated in the accompanying drawings, and more particularly pointed out in the appended claims.

In the drawings:

Figure 1 is a perspective view of the improved grater.

Figure 2 is a vertical, longitudinal sectional view of my grater.

Figure 3 is a transverse sectional view of the grater.

Figure 4 is a view in end elevation of the grater.

Figure 5 is an enlarged fragmentary sectional view taken on line 5—5, Figure 1, and looking in the direction of the arrows.

Referring to the drawings by numerals, 1 designates a flat base which has upstanding inwardly curved or troughed sides 2, forming "springs" adapted to take up any undue pressure placed upon the grater when 45 using the same. The top edges of the spring sides are connected by a concaved seat 3, in which the casing 4 is firmly and permanently seated. The body of said casing is substantially cylindrical and is open at its 50 top. The rear of said body is continued upwardly on a slight outward incline, which together with similarly arranged end portions provide a guiding hopper 5 for conveying the material to be grated or crushed.

The ends of the cylindrical body are provided with vertical slots 6 that extend from

their upper edges to the center thereof, the upper ends of said slots being flaring, and the lower ends being rounded, to provide 60 bearings 7. At the lower portion of one of said ends and preferably in alignment with the slot 6 therein, (Figs. 1 and 2), a drain cock 8 is provided, which communicates with the lower part of the interior of the casing, and by means of which the liquid contents 65 thereof may be drained off. I provide a sieve or strainer 9 to efficiently strain the liquid or fluids passing off through drain cock 8 (Fig. 2).

The upper longitudinal edge of the casing 4 has a hinge connection with a cover 10 for closing the top of said casing, said cover 10 being integral with an angularly projecting cover 11 for the front of the hopper 5, the cover 11, in turn, having a hinge 70 connection with a cover 12 for the top of said hopper 5. This arrangement of covers provides means whereby the top of the hopper may be opened without opening the front thereof or opening the cylinder 4; 75 and also permits both the hopper and the casing to be opened, the independent opening of the hopper being for the purpose of regulating the feed of material, and the opening of the casing being for the purpose 80 of removal of the grated material or to permit cleaning of the casing and hopper, as will be readily understood. Each "section" 85 or cover 10, 11 and 12 has at its ends vertical flanges 13 that overhang the ends of the grater for keeping the contents of the casing and the hopper from spilling out. Each 90 end of the hopper cover 12 is provided at its flange 13 with an outstanding lug 14 (Fig. 1) adapted to be engaged by a pivoted 95 latch 15, so that said cover may be detachably fastened in a hopper-closing position.

A grating or crushing cylinder 16 has its body portion provided with a plurality of rows of struck-up spurs 17. Said cylinder 100 16 is of a size to permit free rotation of the same within casing 4, and has its ends threaded as indicated at 18 (Fig. 2) for the reception of the threaded caps 19. Said caps 19 can also be secured to cylinder 16 by 105 catches, similar to those used for securing preserve jar tops in position. One end cap carries a stub shaft 20, the other cap carries a shaft 21. The shafts 20 and 21 are adapted to be fitted within the end slots 6 of the 110 casing 4 and rotate in the end bearings 7 thereof. Said shafts project beyond their

bearings, and are removably held therein by the end latches 22 that are pivoted at 23 to one side of said slots 6 and are provided with a notch 24 (Fig. 1) which engages over shafts when said latches are rotated to straddle the shaft. The latches 22 are formed of flat metal and are of sufficient size to entirely close the vertical slots 6, thereby preventing any of the contents of the casing 4 from spilling. The top edge of the end latches 22 fits snugly under the flanged ends of the cover 10, whereby the cover acts as a locking means, when closed upon the casing 4, for preventing pivotal movement of the end latches and displacement of the shafts off their bearings 7. Each end latch 22 is provided with an operating grip 25. It will, therefore, be seen that the end latches perform two functions, to wit: they retain the shafts and crushing cylinder in place as well as close or seal the V-shape slots 6; the end latches being held against pivotal movement, and snugly against the ends of casing 4 by the binding and clamping action of the cover and its end flanges when closed upon the casing.

The shaft 20 terminates in a crank handle 26, which is equipped with a grip 27 by means of which the grating cylinder may be manually operated. Said shaft 21 also carries a pulley 28, by means of which the shaft may be placed in belted communication with a motor for operating the cylinder, when necessary or desirable.

To efficiently fasten my grater to table 29, I preferably employ four screws 30, extending through the curved side 2 and base 1 into the table, as clearly shown in Figures 1 and 5. To prevent these screws 30 from having a tearing action on the metal through which they pass, I provide for each, a primary sleeve 31 enclosing and slidably mounted upon an auxiliary sleeve 32 (Fig. 5). Each of the sleeves 31 and 32 extend into apertures of the base and sides, so that the apertures are reinforced, with no cut or "raw" edge exposed, hence their tearing possibilities are greatly decreased. The primary sleeve is provided with a flat collar 33 that rests flat upon the top face of the curved side, which further increases the durability and efficiency of my grater by giving a good bearing surface for the head of the screw. During the life of my grater, considerable strain is exerted upon the spring sides 2 and seat 3, which causes them to have movements indicated by dotted lines A, in Figures 3, 4 and 5. Now, the screw-structures not only efficiently fasten my grater to a support, such as table 29, but they also brace the whole

apparatus against sagging or twisting or undue bending, which is very desirable, because practically a rigid and durable structure is produced, yet adhering to the simplicity of construction, not only outlined in this case, but also generally outlined in my prior Patent No. 977,872, hereinbefore mentioned.

It will be seen from the foregoing that the improved machine provides simple and effective means for sealing the hopper and casing, and also simple means for retaining the grating cylinder securely in place within said casing. Another feature of my apparatus is the employment of removable end caps, held by any suitable fastening means upon the grating cylinder, which can be readily removed to give access to the interior of said cylinder.

While I have described the preferred embodiment of my invention and illustrated the same in the accompanying drawings, certain minor changes or alterations may appear to one skilled in the art to which this invention relates during the extensive manufacture of the same, and I, therefore, reserve the right to make such changes or alterations as shall fairly fall within the scope of the appended claims.

What I claim is:

1. In an apparatus of the class described, the combination of a casing provided with ends, said ends provided with shaft receiving slots, a cylinder with shafts seated in said slots, end latches on the ends of said casing and normally straddling said shafts and entirely closing said receiving slots, and a cover for said casing normally closing over and bearing upon said end latches for holding them in a locked position.

2. In an apparatus of the class described, the combination of a casing provided with substantially V-shaped slots having bearings formed at their inner ends, a cylinder provided with shafts extending from its ends, said shafts journaled in the bearings of said V-shaped slots, large flat end latches pivotally secured to the ends of said casing and straddling said shafts and entirely closing said V-shaped slots and extending to the top edge of said casing, and a cover for said casing provided with end flanges bearing against the sides of said end latches and the cover bearing upon the top of said end latches whereby the latches and shafts are held in position against displacement off said cylinder.

In testimony whereof I hereunto affix my signature.

AUGUSTA DU BUISSON HOPKINS.
